UNITED STATES PATENT OFFICE.

OTTO EDLER, OF HANOVER, GERMANY.

SEAL-LOCK.

935,195.

Specification of Letters Patent. Patented Sept. 28, 1909.

Application filed April 2, 1909. Serial No. 487,519.

To all whom it may concern:

Be it known that I, OTTO EDLER, a citizen of Germany, residing at Hanover, Germany, have invented new and useful Improvements 5 in Seal-Locks, of which the following is a specification.

This invention relates to the seal locks of books, more particularly loose-leaf ledgers or the like and has for its object to provide 10 a device which will prevent unauthorized use of the key whereby the book is opened or pages removed.

According to this invention a flat box is disposed above the keyhole and provided 15 with slots on its upper and under surfaces, the lower slot being adapted to receive the keyhole rim, while the upper slot is of such shape that two paper or similar strips can be introduced through it into the two lateral 20 portions of the box. These two paper strips which cover the keyhole, are then connected together by means of a seal or the like, so that it is impossible to get to the keyhole without destroying the seal.

One construction according to this invention is illustrated by way of example in the accompanying drawings, in which—

Figure 1 is a perspective view of a loose-leaf book, provided with my improved seal lock, Fig. 2 is a plan of the box, and Fig. 3 is a central cross section of Fig. 2.

In the construction shown the keyhole *a* of the loose-leaf book *b* (Fig. 1) is adapted to have a box *e* shown in Figs. 2 and 3, 35 used in connection with it as a sealing device. The box *e* is provided on its under

surface with a circular slot *d* adapted to surround the keyhole rim *c*, and on its upper surface has an opening *f* which enables two paper strips *g*, *h* to be introduced into the 40 box, the superimposed edges of which are then connected by a seal *i*. This seal is so positioned that it extends over the overlapping edge of strips *g*, *h*, and is pasted on one 45 side of said edge to strip *g*, and on the other side to strip *h*. Without destroying the seal, it is then impossible to get to the keyhole *a*.

Although particularly intended for use in connection with loose-leaf ledgers and the like the device may also be used on the 50 ordinary volumes closed.

What I claim is:

1. A seal lock for loose-leaf or other books comprising two strips of paper or the like 55 inserted between the keyhole and projections above the latter and having their superimposed edges connected by a seal as set forth.

2. A device of the character described, 60 comprising a box having a lower slot adapted to receive a key hole rim, an upper opening, a pair of overlapping paper strips interposed between said slot and opening, and a seal projecting over the overlapping edges 65 of said strips.

Signed by me at Hanover, Germany, this eighteenth day of March 1909.

OTTO EDLER.
